UNITED STATES PATENT OFFICE.

AUGUST NETHERLAND, OF NEW YORK, N. Y.

DESIGN FOR A DISH.

SPECIFICATION forming part of Design No. 29,168, dated August 9, 1898.

Application filed May 23, 1898. Serial No. 681,518. Term of patent 14 years.

To all whom it may concern:

Be it known that I, AUGUST NETHERLAND, a citizen of the United States, residing at New York, (Brooklyn,) in the county of Kings and State of New York, have invented and produced a new and original Design for Dishes, of which the following is a specification, reference being had to the accompanying drawings, forming a part thereof, in which—

5 Figure 1 represents a plan view of a dish constructed according to my design, and Fig. 2 is a vertical central section through the same.

The leading or characteristic feature of my 15 design consists of the dish 1, having a border 2 around its outer edge formed by upwardly-extending flanges 3 4, the inner of which is circular and the outer of which is substantially parallel thereto except that at two diametrically opposite points, as at 5, the same 20 is formed with segmental offsets, as clearly shown. Within the border 2 referred to are arranged a series of circular panels containing representations of the seven Ferdinands 25 of Spain and their coats-of-arms, the said

panels arranged at regular intervals. Two of the panels, being represented upon the drawings by the numeral 7, are located at diametrically opposite points, are somewhat larger than the others, and are arranged within the 30 segmental offsets formed in the border 2. Within the border 2 the dish is depressed, as shown at 8, and at the center of the depressed portion is a circular panel 9, in which is contained a design representative of the fight for 35 Scotland, said design containing a number of warriors massed together in the costumes of the thirteenth century, some lying on the ground in disabled condition and others carrying battle-axes and other weapons of war. 40

What I claim as my invention is—

The design for a dish, substantially as shown and described.

In testimony whereof I affix my signature in presence of two witnesses.

AUGUST NETHERLAND.
